UNITED STATES PATENT OFFICE.

JAMES C. MEEM, OF BROOKLYN, NEW YORK, ASSIGNOR OF TWO-THIRDS TO THE BOROUGH CONSTRUCTION COMPANY, OF BROOKLYN, NEW YORK.

METHOD OF TUNNELING.

SPECIFICATION forming part of Letters Patent No. 795,148, dated July 18, 1905.

Application filed October 14, 1903. Serial No. 177,054.

To all whom it may concern:

Be it known that I, JAMES C. MEEM, a citizen of the United States, residing at Brooklyn, in the county of Kings and State of New York, 5 have invented a new and useful Method of Tunneling, of which the following is a specification.

This invention relates generally to methods of tunneling, and more particularly to methods for constructing large tunnels in which it is necessary to carry forward the excavation at a plurality of different levels.

The general object of the invention is to improve methods of tunneling, so that excavations may be carried forward simultaneously at a plurality of different levels at a maximum rate of speed and without material danger of collapse of the supporting structures employed in the tunneling processes.

With this and other objects in view, as will appear when the invention is better understood, the same consists in the improved method of tunneling hereinafter fully described and claimed.

In describing the invention reference will be had to the accompanying drawings, forming part of this specification, in which there is illustrated by a series of figures of somewhat diagrammatic character the manner in which a tunnel is constructed in accordance with this invention, it being understood that the apparatus exhibited may be varied or changed as to shape, proportion, and exact mode of assemblage of the elements without departing from the spirit of the invention or sacrificing the advantages thereof.

In the drawings, Figure 1 is a view in longitudinal section through a portion of a tunnel in process of construction. Fig. 2 is a 40 transverse sectional view of a small tunnel being advanced on a single level. Fig. 3 is a transverse sectional view of a large tunnel, showing the procedure in advancing on several levels, the right-hand side of the figure being taken on the line *a a*, Fig. 1, and the left-hand side of the figure being taken on the line *b b*, Fig. 1. Figs. 4, 5, and 6 are detail views of different portions of the structure employed.

In its entirety this invention comprises 50 novel methods of carrying forward the supporting structures beneath the tunnel - roof simultaneously with the progress of the excavation in the uppermost level of the tunnel, novel methods of construction and carrying 55 forward the roof-supporting structures at a lower level simultaneously with the advance of the excavation at the lower level, and novel methods of bracing and tying together the elements of the supporting structure within 60 the tunnel as said supporting structure is extended forward.

In constructing a tunnel in accordance with this invention the advance of the top lagging of the roof-support simultaneously with the 65 excavation is effected by the use of caps or supports of the character best shown in position in Fig. 2 and in detail in Figs. 4, 5, and 6. Each cap comprises cross-beams 1, each provided on its upper surface with a double 70 tier of upright members 2, formed, preferably, of sections of "I-beams" and separated by a supporting member 3, preferably of metal. The upper tier of the spacing members 2 of each cap affords support for a waling-piece 4, 75 preferably of planking, and the spacing members 2 of both tiers are arranged at such intervals that lagging or poling boards 5 and 5^a may be introduced between them and driven forward in the directions indicated in the 80 drawings without interference from the spacing members.

In constructing each cap or support for the lagging-boards the lower tier of spacing members 2 is first fixed upon the cross-beam 1. 85 The supporting-piece 3 is then fixed upon the spacing members of the lower tier, and the spacing members of the upper tier are then fixed in position upon the supporting-piece, the waling-piece being detached from the upper tier of spacing or readily detachable therefrom, although all the pieces of material forming the cap may be detached, if desired.

In operating with caps of the character just described, assuming the set of lagging-boards 95 5 to be in position and the supporting-caps therefor to be also in the position indicated in Fig. 1, a set of lagging-boards 5^a is intro-

duced in the position indicated in dotted lines in Fig. 1 and the excavation is carried forward from the foremost cap shown in Fig. 1, and the lagging-boards are driven forward as the excavation proceeds beneath the roof. After the lagging-boards 5^a have been driven forward to a sufficient distance cantaliver-beams 6 are introduced beneath the foremost cap and supported upon uprights 7, as best seen in Fig. 2, and the lagging is then blocked up from the cantaliver-beams, as shown in Fig. 1. The excavation is then carried forward to the extent shown in Fig. 1 and the lagging-boards 5^a are simultaneously driven forward, the driving forward of the lagging-boards being facilitated by the beveled forward ends thereof. (Best seen in Fig. 4.) The excavation is then extended downward to the level at which the supports for the caps are positioned, and another cap is then set up under the forward ends of the boards 5^a and a new set of lagging-boards is introduced under the boards 5^a in the manner already explained. The excavation is then carried forward and the new set of lagging-boards advanced in the manner just explained.

As each new cap is placed in position under the foremost set of lagging-boards the cantaliver-beams and the blocks supported thereby are removed and are laid aside until the excavation has proceeded forward sufficiently to permit their introduction to afford temporary support for the next set of lagging-boards.

In selecting lagging-boards proper care must be exercised to insure the free movement of the lagging-boards between the spacing members without jamming, and in introducing the boards they must be set in the inclined position shown in Fig. 1, the forward ends of each set of lagging-boards being disposed between the spacing members of the upper tier of standards of the forward cap, and the rear ends of each set of lagging-boards being disposed between the spacing members of the lower tier of the rear cap. In this way the rear ends of each set of lagging-boards when in final position are overlapped by the forward ends of the set of lagging-boards just behind.

In placing the caps in position as the lagging is advanced any preferred form of temporary support may be used. Afterward the temporary support must be removed and end posts 8 put in place to give sufficient support to the lagging and roof.

The lagging-boards used in connection with the cap in forming the supporting structure for the tunnel-roof are preferably notched at their rear ends, as shown at 9 in Fig. 4, so that the caps may be withdrawn without interference of the lagging with the spacing members 2. When each cap is withdrawn, the waling-piece 4 is left in position between the ends of the adjacent sets of lagging, and

other supports are introduced in lieu of the 65 caps, which are employed, primarily, to afford a support and guidance to the lagging-boards as they are driven forward simultaneously with the advance of the excavation.

By repeating the operation described in the 70 preceding paragraphs as fast as the excavation is carried forward sufficiently to permit of the erection of the supporting-blocks, cap, and cantaliver-beams the lagging at the roof of the tunnel may be made continuous and collapse of the tunnel-roof prevented. 75

The standards upon which the cap is supported rest on sills 10, as shown in Fig. 2. Temporary bridging-beams 11 are laid across the sills 10 in a longitudinal direction, and cross-beams 12, formed, preferably, in sections and bolted together, are positioned on these latter beams. Bearing-caps 13 are then positioned in front just ahead of the heading-caps and are blocked up from the cross-beams 12. 80 Longitudinal excavations are then made, (and sheeted, if necessary,) and in the longitudinal excavations two or more rows or sets of foot-blocks 14 are placed. Temporary supports are next placed under the cross-beams resting upon the foot-blocks, and caps 15 are positioned under the cross-beams. Inclined props 16 are then run from the foot-blocks to the caps 15 to give them permanent support. The caps 15 take the load of the cross-beams, 95 while these props 16 are introduced in place of the temporary supports.

The procedure outlined in the preceding paragraph may be varied in good ground, if desired, by omitting the caps 15 and props 16 100 and making the uprights from the foot-blocks permanent.

Suitable support for the cross-beams having been positioned upon the foot-blocks, a trench is then excavated and sheeted between 105 and below adjacent sets of foot-blocks, and a foundation is placed therein on which posts or props may be put to support longitudinal beams 17, from which the roof-supports are again blocked while the sides and bottom excavations are completed. 110

The completion of the tunnel-roof from the point reached may proceed by any desired method according to the nature of the proposed design, as the succeeding steps in a tunnel construction do not depend upon the method above outlined and form no part of the present invention. 115

The longitudinal beams 17 form a special feature of the present method of tunneling 120 and are preferably of one of the forms now to be described. The preferred design is that illustrated in Fig. 5, in which a beam is shown as made up of steel channels bolted together to form I-beams, the channels being so arranged that the ends of each member overlap the ends of the members next thereto on the opposite side, so that they abut against the 125

ends of the adjacent members on the same side. By arranging the members of the beam in this manner, with the joint between the two members on one side exactly opposite the middle of a member on the other side, the greatest strength is obtained in the beam, and by constructing the beam in this way longitudinal supporting-beams may be formed which are much longer than any integral beams which could be introduced through the tunnel-shaft. While steel channels are preferred for the construction of the beams 17, timbers of rectangular cross-section may be arranged in the same manner, and T-beams, flat bars, angles 15 Z-bars, or bars of any other desired shape may be employed instead, provided they may be bolted or otherwise fastened together.

In lieu of the beams formed of sections bolted together in the manner illustrated in Fig. 5, I-beams having ends cut away so as to overlap, as illustrated in Fig. 6, may be substituted; but it will be obvious that the bolts employed to connect the beam-sections will then be subject to greater strain than in the preferred structure. As the tunnel construction proceeds the rear end members of the beam may be detached and carried forward to be again bolted into place. Thus it is evident that by means of sectional-beam structure all 30 the advantages obtainable from strong beams whose length is too great to permit them to be introduced through the tunnel-shaft are gained and the unwieldiness of such beams is avoided. Such sectional beams may be used 35 to advantage not only as continuous string-beams 17, but in lieu of the cross-beams 12 and as tie-bars 18, hereinafter described.

While this system of tunneling is intended for use primarily without the employment of 40 compressed air within the tunnel, the introduction of locks and such other appliances as are required for the use of compressed air has been provided for, so that compressed air may be used in connection with this method of 45 tunneling, if so desired.

In soft ground the introduction of cast iron or steel pipes 19, filled with concrete or other form of piling, on which to rest the sills, foot-blocks, or the bottom of the structure, may be 50 included in this method of tunnel construction, and by using some form of piling for the purposes specified this system of tunneling may be employed where ordinarily compressed air would have to be introduced. It may also be 55 desirable in soft ground to "tie" the caps of the supporting structure beneath the tunnel-roof together by longitudinally-disposed connections, and this may be conveniently done by inserting under the caps continuous beams 60 (preferably constructed as shown in Fig. 6) and blocking up the beams from the cross-beams 12, as shown at 18 in Figs. 1 and 3.

It is to be understood that the bracing herein described may be applied to excavations a

portion of which has been taken out in an 65 open cut and which has been wholly or partly boarded over, as well as to excavations made wholly in a tunnel.

Having thus described my invention, what I claim is—

1. A method of tunnel construction consisting in placing a support having horizontal series of passages beneath the tunnel-roof, then introducing lagging through the said passages, advancing the lagging into the heading of the 75 tunnel, excavating beneath the lagging, and placing a second support having like passages under the forward ends of the lagging-boards.

2. In a method of tunneling, the step consisting in constructing and introducing beneath the tunnel-roof a cap having passages, 80 then passing lagging-boards through the passages when the cap is in place, advancing said boards, excavating beneath them and finally setting a second cap under the forward ends 85 of said lagging-boards when they have been driven into place.

3. In a method of tunneling, the step consisting in introducing beneath the tunnel-roof supporting-caps, each having two superposed 90 tiers of spacing members, then introducing lagging-boards through the openings between the upper tier of spacing members of the forward cap and the openings between the lower tier of spacing members of the rear cap, driv- 95 ing said lagging-boards forward, supporting the lagging temporarily, excavating below the lagging, placing another cap beneath the forward ends of said lagging-boards, blocking up said cap and removing the temporary 100 support of the lagging.

4. In a method of tunnel construction, the step consisting in introducing beneath the tunnel-roof a supporting structure having two superposed sets of spacing members, inserting 105 lagging-boards through the spaces between the upper set of spacing members, excavating in front of said supporting structure and advancing said lagging-boards simultaneously with said excavation, introducing a second 110 supporting structure beneath the forward ends of said lagging-boards when advanced to the proper distance, introducing a second set of lagging-boards through the openings between the lower spacing members of the first sup- 115 porting structure and between the upper spacing members of the last supporting structure, excavating in front of said last support and advancing said set of lagging-boards simultaneously with the advance of said excavation.

5. In a method of tunnel construction, the procedure consisting in excavating beneath the tunnel-roof, then placing temporary supporting structures each having two sets of super- 125 posed spacing members thereon in position beneath said roof, introducing lagging-boards between said spacing members as the excavation

- is carried forward and driving said lagging-boards between said spacing members of the foremost supporting structure simultaneously with the advance of the excavation, placing permanent supporting structures in position beneath said lagging-boards and removing said temporary supporting structures after the permanent supporting structures have been placed in position.
- 10 6. In a method of tunnel construction, the procedure consisting in excavating upon an upper level, sheeting and blocking the excavation in any preferred manner, setting cross-beams in said excavation, excavating beneath said cross-beams and setting foot-blocks in the excavation formed, blocking up the tunnel-roof from said foot-blocks, sheeting and excavating an open trench between the foot-blocks, placing a foundation in said trench, blocking up longitudinal beams from said foundation and proceeding in any preferred manner from that point.
- 15 7. In a method of tunnel construction, excavating, sheeting the excavation, blocking up the roof, setting foot-blocks in the excavation, excavating below said foot-blocks, placing a foundation in said excavation, blocking up

longitudinal members secured together to form continuous beams, mounting roof-supports upon said beams, and carrying forward 30 the beams by detaching the rear members from said beams, carrying them forward and securing them in position at the forward ends of said beams.

8. In a method of tunnel construction, the 35 procedure consisting in introducing into the excavation sectional string-beams, erecting temporary supporting structures successively above and below said beams, removing the rear structures, section by section, removing 40 the rear end sections of the string-beams and carrying them forward and securing them to the forward ends of the string-beams and erecting the temporary supporting structures removed from the rear, or substituting new ones 45 therefor.

In testimony that I claim the foregoing as my own I have hereto affixed my signature in the presence of two witnesses.

JAMES C. MEEM.
